PRINTING MACHINE

Walter T. Gollwitzer, Chicago, Ill., assignor to Addressograph Company, Wilmington, Del., a corporation of Delaware

Application November 2, 1931, Serial No. 572,489

11 Claims. (Cl. 192—132)

This is a continuation in part of my application, Serial No. 469,953, filed July 23, 1930.

This invention relates to printing machines of the kind wherein printing devices are sequentially fed through printing position. An anvil is provided below an opening in the bed of the machine and the printing devices rest on the anvil during printing operations. An ink ribbon is stretched over the printing device at printing position and a shield having an opening therein is arranged over the ribbon. The sheet is placed on the bed of the machine with the portion thereof to receive the impression aligned with the openings in the bed and in the shield, and a platen is operated to make an impression on the sheet through the ink ribbon from the printing device.

The general object of my invention is to provide a novel safety device in a printing machine to prevent injury to the operator's fingers and damage to the machine in the event the operator's fingers or other obstruction lies in the path of the platen during movement thereof toward printing position and to this end I so operate the platen that impression pressure is not applied thereto during movement thereof toward printing position unless and until the platen is so close to printing position that there is not sufficient room for a finger or other obstruction to be disposed between the platen and the sheet to receive the impression.

Another object of the invention is to provide a printing machine wherein the driving means for the platen operate during each cycle of operation of the machine but wherein the platen is operated and connected to the driving means only during determined cycles of operation so that the platen may be held in a non-printing position without interrupting operation of the driving means therefor and I thereby overcome difficulties attendant to overrunning of the driving means when movement thereof is interrupted and I also obviate the necessity of overcoming the inertia of stationary driving means when it is to be set in operation in a cycle following one wherein movement thereof was interrupted.

A further object of the invention is to provide a printing machine wherein when a printing operation is to be performed the platen will move toward printing position without being connected to the driving means therefor until it attains a predetermined position so that the platen may be grasped or otherwise held against movement at any time prior to its movement into said predetermined position and wherein the platen is

moved into non-printing or at rest position by the driving means thereof each time the platen moves from its non-printing position even though it may be prevented from moving into said predetermined position.

In the selected embodiments of my invention illustrated in the accompanying drawings

Fig. 1 is a fragmentary side elevation of a printing machine including my invention;

Fig. 2 is a fragmentary sectional view looking in the direction opposite to Fig. 1;

Fig. 3 is a detail view similar to Fig. 2 and showing the parts in another position;

Fig. 4 is a fragmentary sectional view looking in the same direction as Fig. 1; and

Fig. 5 is a view showing the device as arranged for manual operation.

To illustrate the invention, I have shown a machine embodying a stamper platen, but it is to be understood that the invention may be used with machines embodying other types of platens. To operate the machine, I employ an electric motor (not shown) and a belt 8 is directed about a pulley on the shaft of the motor and a pulley 9 on the jack shaft 10 journaled in bearings in the frame. The main drive shaft 11 is journaled in bearings carried by the frame and rotatably mounted thereon is a spur gear 12 meshing with a pinion 7 fast on the jack shaft 10. On the main drive shaft is a suitable one-revolution clutch 13 controlled by a rod 14 connected to the arm 15 pivotally mounted at 16 on the bracket 17 carried by the frame 6. An eccentric 18 is mounted on the bracket 17 and by moving the most eccentric portion thereof into engagement with the arm 15, the rod 14 is so moved that the clutch 13 is engaged to connect the gear 12 with the shaft 11. A rod 19 is connected to the arm 15 and to a foot pedal 20 mounted on the frame and by depressing the foot pedal 20, the arm 15 is moved and therefore the rod 14 is so moved that the clutch is engaged. A spring 21 acts on the arm 15 to urge the rod 14 upwardly to disengage the clutch 13. The foot pedal 20 is usually employed to bring about cyclic operation of the machine while the eccentric 18 is used to bring about continuous operation since it will hold the arm 15 in such a position that the rod 14 will keep the clutch engaged. Movement is transmitted by the belt 8 from the motor to the jack shaft and through the pinion 7, gear 12, and clutch 13 to the shaft 11 when the clutch is engaged.

Impressions are made from printing devices fed in a step-by-step manner through the print-

ing device guideway 22 to printing position above the anvil 23 by a suitable mechanism, one form of which is disclosed in my referred to co-pending application Serial No. 469,953, filed July 23, 5 1930. The impressions are made through an ink ribbon (not shown) stretched over the printing device in printing position and a step-by-step movement is imparted to the ribbon by a suitable mechanism as, for example, such as that disclosed 10 in my co-pending application Serial No. 467,783, filed July 14, 1930.

Impressions are made from the printing device through the ink ribbon onto the sheet by platen P which may be of the kind disclosed in my co-pending application Serial No. 467,784, filed July 14, 1930. The platen is mounted on the shaft 25 journaled in bearing disposed adjacent the rear edge of the bed. Formed as an extension of the platen arm 24 is an arm 27 which depends below the shaft 25. At the lower end of the arm 27 is a half-round lug 28. An arm 29 pivotally mounted at 30 on a bracket 31 depending from the bed 26 has a notch 32 in the upper edge thereof. The lug 28 seats in the notch 32 to hold and latch 20 the platen arm in its at rest or non-printing position. Suitable means to be described more fully hereinafter are provided for pivoting the arm 29 in a counter-clockwise direction as viewed in Fig. 2 whereby the notch is retracted from engagement with the lug 28 to unlatch the platen arm 24 which then pivots about the shaft 25 by reason of the weight of the overhanging extent thereof and the weight of the platen at outer end. This downward pivoting movement of the platen arm 30 moves the platen toward printing position. The platen moves toward printing position without being connected to the driving means therefor and the platen so moves until it attains a predetermined position whereat it is so close to the sheet to receive the impression that there is not sufficient room for the operator's finger or other obstruction to be positioned intermediate the platen and the sheet. When the platen moves into such predetermined position, pressure is applied by the connection of the platen arm with the driving means therefor. Until the time pressure is applied to the platen arm it may be freely moved about the shaft 25 or it may be grasped and held against movement. Thus since the platen is not connected to the driving means 40 therefor and as the platen and the arm 24 are made as light as possible consistent with proper operation of the machine, the operator's fingers will not be injured should the platen strike thereagainst nor will the machine be damaged if the platen engages some rigid construction.

At the time the platen moves into the predetermined position, a driving means is connected thereto and impression pressure is applied by the platen. The driving means includes an eccentric disc 33 fast on the main drive shaft 11 and disposed about the periphery of the eccentric is an eccentric bushing 34 which, in turn, is surrounded by a clamp strip 35 retained in position by the clamp portion 36. Unitary with the clamp strip 35 is an arm 37 carrying a block 38 providing a shoulder 39. A pawl 40 is pivotally mounted at 41 at the lower end of the arm 27 on the side thereof and in the plane above the half-round lug 28. The pawl has a nose 42 at one end thereof and a shoulder 43 at the other end. A spring 44 extends between the pawl 40 and a spring anchor on the arm 27 and tends to pivot the pawl in a counter-clockwise direction as viewed in Fig. 3. Fast to the bracket 31 and ex-

tending outwardly therefrom is an arm 45 having a cam surface 46 on the upper edge thereof and when the lug 28 is seated in the notch 32, the spring 44 so acts on the pawl 40 that the nose 42 thereof is held on the cam surface 46. When the platen arm is unlatched to permit the platen to move toward printing position, the nose 42 rides along the cam surface 46 and at the time the platen moves into the above described predetermined position, the nose 42 will reach the end of the cam surface 46 and will fall therefrom whereupon the shoulder 43 is moved into the path of the shoulder 39 defined by the block 38 fast on the arm 37. During the time the nose 42 is traveling along the cam surface 46 the eccentric 33 will be so rotating with the shaft 11 that the arm 37 will be moving away from the shaft, toward the left as viewed in Fig. 3, and at the time the shoulder 43 engages the shoulder 39 the arm 37 will have been so moved as to be close to the limit of its movement in the above described direction but it will continue to move in this direction after the engagement of the shoulders 43 and 39 in an amount sufficient to move the platen into printing position and to apply impression pressure thereto. The arm 37 includes a hook-shaped end portion 47 and a boss 48 is provided on the arm 27 in alignment with the arm 37 and is adapted to be partially embraced by the hook-shaped end portion 47. The pawl 40 is pivotally mounted on the boss 48 at the outer end thereof and the hook-shaped end portion 47 is disposed between the adjacent portion of the arm 27 and the pawl. Immediately after the arm has imparted impression pressure to the platen P the eccentric 33 operates to move the arm 37 toward the shaft 11, to the right as viewed in Fig. 3, and the hook-shaped end portion 47 engages the boss 48, and as the arm 37 continues to move toward the shaft this movement will be imparted to the arm 27 and therefore to the platen arm 24 which will move the platen back into its upper or non-printing position. If the arm 29 has returned to the position shown in Fig. 3, the lug 28 will again seat in the notch 32 whereby the platen will be latched in its non-printing position. However, should the arm 29 not be so positioned that the lug 28 may seat in the notch or when the arm 29 is pivoted to retract the notch 32, the platen arm will be unlatched and will be free to fall as above described and at the time the nose 42 rides off the cam surface 46, the shoulder 43 will again engage the shoulder 39 and impression pressure will again be imparted to the platen.

If some obstruction lies in the path of the platen after it has been unlatched and the platen is prevented from moving into the predetermined position, the nose 42 will not move to the end of the cam surface 46 and hence the shoulder 43 will be prevented from moving into the path of the shoulder 39 and consequently no impression pressure will be imparted to the platen. Since impression pressure cannot be imparted to the platen until it attains the predetermined position and until the shoulder 39 on the arm 37 has moved sufficiently to engage the shoulder 43 should said shoulder lie in the path of the shoulder 39, it is apparent that the platen arm 24 may be grasped and pivoted about the shaft 25 and unless and until the platen moves into the predetermined position, the shoulder 43 will be prevented from moving into the path of the shoulder 39. However, the hooked end portion 47 is always disposed in position to engage the boss 48 and therefore even though the platen does not

move into the predetermined position or should it be held in some position whereat the nose 42 is prevented from disengaging the cam surface 46, the hooked end portion 47 will engage the boss 48 at some time in the travel thereof and consequently the platen arm will be moved back into non-printing position every time it is released whether or not impression pressure is applied thereby. 10 In my co-pending application, Serial No. 469,953, I have described a selector mechanism for controlling the operation of the platen from the printing devices. This selector mechanism includes a head H wherein a plurality of detecting fingers F are arranged which are positioned by engagement with identifying characteristics on the printing devices and these positioned fingers, in turn, cooperate with a matrix to regulate the positioning of the arm 52 which, in turn, determines the positioning of an arm 53 having a triangularly shaped lug 54 mounted adjacent the end of the upwardly extending end portion of the arm 53. Pivotally mounted at 30 is an upwardly extending arm 55 and connected thereto so as to be movable therewith is an arm 56, and a spring 57 extends between a spring anchor 58 positioned on the arm 29 adjacent the notch 32 and a spring anchor 59 on the arm 56. Another spring 60 extends between a spring anchor 61 positioned on the arm 29 on the side of the pivotal mounting opposite that whereat the spring anchor 58 is positioned and a spring anchor 62 on the bracket 31. In the edge of the arm 55 disposed toward the shaft 11, there is a V-shaped notch 63 and the edge is tapered adjacent the free end of the arm as indicated at 64 whereby an apex 65 is defined which is in alignment with the edge 66 of the arm 55. Whenever the arm 53 is so positioned that the apex of the triangularly shaped lug 54 seats on the apex 65 or the surface 66, the arms 55 and 56 are pivoted. Pivoting on the arm 56 tends to elongate the spring 57 whereby the arm 29 is pivoted in the counter-clockwise direction, previously described, against the action of the spring 60, the spring 57 being heavier than the spring 60. So long as the apex of the triangularly shaped lug 54 seats on the apex 65 or the surface 66, the arm 29 will be held in this lower position but should the arm 53 be so positioned that the triangularly shaped lug is disposed in the V-shaped notch 63 or on the tapered surface 64, the spring 60 will act to pivot the arm 29 and consequently the arms 56 and 55 into the position illustrated in Fig. 3 whereby the notch 32 will be so positioned that the lug 28 may seat therein. 15

It is sometimes desirable to equip a printing machine with a manually operable skipping device which may be employed to hold the platen in non-printing position should it be desired not to perform a printing operation from a certain printing device. One arrangement which may be employed for this purpose is illustrated in Fig. 5, and herein the platen operating mechanisms heretofore described are illustrated. In this instance however a rod 49 is pivotally connected to the arm 56 and this rod extends to the front of the machine whereat a knob 50 is provided, the rod extending through an opening 51 in the apron 51 at the front of the machine. The rod 49 is provided with a flattened portion and notches 50' and 49' are provided in the lower edge of this flattened portion, either of which notches may be engaged with the portion of the apron adjacent the opening 51'. When the notch 49' engages the apron, the rod 49 so positions the

arm 56 that the spring 60 may act to move the arm 29 into a position whereat the notch 32 will engage the lug 28. However, when the notch 50' is engaged with the apron, the rod 49 will so position the arm 56 that the spring 57 will act on the arm 29 to retract said arm from a position whereat the lug 28 will seat in the notch 32. Therefore, when the rod 49 is arranged as shown in Fig. 5, the platen will be latched in an upper or non-printing position whereby any desired printing device or series of printing devices may be passed through the machine without printing operations being performed therefrom and thus these printing devices are, as it is termed, skipped. 20

It is manifest from the foregoing description that I have provided a novel safety device for use with a printing machine which will so function that injury to the operator's fingers or damage to the machine will be prevented for impression pressure is not applied to the platen unless and until it moves into a position so close to the sheet to receive the impression that there is not sufficient room for a finger or other obstruction to be disposed intermediate the platen and the sheet. Furthermore the platen will always move into its upper or non-printing position after it has been unlatched whether or not it performs a printing operation for the means which move the platen back into non-printing position function during each cycle of operation of the machine and consequently, even though the platen is grasped and held against movement, the means for moving the platen back into non-printing position will engage the device operating therewith at some time during movement thereof. 25

In the foregoing description I have set forth selected embodiments of my invention but it is to be understood that these are capable of variations and modification and I therefore do not wish to be limited to the precise details set forth but desire to avail myself of such changes and alterations as fall within the purview of the following claims. 30

I claim:

1. In a device of the class described, a pivotally mounted arm movable between an operative and an inoperative position, said arm including a portion below the pivotal mounting thereof, latching means cooperating with the depending portion of said arm for latching said arm in inoperative position and including a movable member, and means for moving said movable member for unlatching said arm whereby the arm may move toward operative position. 35

2. In a printing machine which has means sequentially feeding printing devices through printing position in the machine, a pivotally mounted platen arm, and a platen on said platen arm and movable between printing position in the machine and a non-printing position, the combination therewith of means for latching said platen arm to hold said platen in non-printing position and including a pivotally mounted arm, and means yieldably connected to said arm and including a manually operable rod for controlling the operation of said latching means. 40

3. In a device of the class described, a pivotally mounted arm having a part depending below the pivot therefor, a dog pivotally mounted at the lower end of said part, a cam plate upon which the dog rides, and means for driving said arm when said arm moves into a predetermined position and including a member engageable by said dog when said dog rides off the end of said 45

cam plate as said arm moves into said predetermined position.

4. In a device of the class described, a pivotally mounted arm having a part above its pivot and a part depending below the pivot therefor, a dog pivotally mounted at the lower end of said last named part, a cam plate upon which the dog rides, and means for driving said arm and including a member adapted to be disconnected from said last-named part during the major portion of the descent of the first named part of said arm and engaged with said last named part to effect ascent of said first named part and including a device adapted to be engaged by said dog when said first named part moves into a predetermined position and said dog rides off the end of said cam plate as said first named part moves into said predetermined position.

5. In a device of the class described, a frame, a platen arm pivotally mounted in said frame and having a part depending below the pivot therefor, a dog pivotally mounted at the lower end of said part, a cam plate fast on said frame and upon which the dog rides, driving means mounted in said frame and including a reciprocating arm adapted to be disconnected from said part during the major portion of the descent of said platen arm and adapted to be engaged with said part to effect ascent of said platen arm, and means on said reciprocating arm and engageable with said dog when said platen arm moves into a predetermined position and said dog rides off the end of said cam plate.

6. In a device of the class described, a frame, a platen arm pivotally mounted in said frame and having a part depending below the pivot therefor, a dog pivotally mounted at the lower end of said part, a cam plate fast on said frame and upon which the dog rides, a drive shaft, an eccentric on said drive shaft, a band surrounding said eccentric and having an arm connected thereto including a hook at the free end thereof, a boss on said part and adapted to be engaged by said hook to effect ascent of said platen arm upon movement of the arm operated by said eccentric in one direction, and means on said arm engageable with said dog upon movement of said arm in the other direction and when said platen arm moves into a predetermined position and said dog rides off the end of said cam plate.

7. In a device of the class described, a pivotally mounted arm having a part above its pivot and a part depending below the pivot therefor, a boss at the lower end of said last named part, a latch engageable with said boss to hold the first named part of said arm in an elevated position, and means including a yieldable portion for retracting said latch to permit descent of said first named part from said elevated position.

8. In a device of the class described, a pivotally mounted arm having a part above its pivot and a part depending below the pivot therefor, a dog pivotally mounted at the lower end of said

last named part, a cam plate upon which the dog rides, driving means and including a hook engageable with said last named part to effect ascent of the first named part of said arm and permit free descent of said first named part and including another part engageable with said dog when said dog rides off the end of said cam plate when said arm moves into a predetermined position in the descent thereof, a boss on said last named part, a latch adapted to engage said boss to hold said first named part in an elevated position into which it is moved by said driving mean whereby said driving means may be operated without a consequent descent and ascent of said first named part when said latch is engaging said boss, and means for engaging said latch with said boss to retain said first named part in said elevated position during selected operations of said driving means.

9. In a printing machine which has means sequentially feeding printing devices through printing position in the machine, a pivotally mounted platen arm, and a platen on said platen arm and movable between printing position in the machine and a non-printing position, the combination therewith of means for latching said platen arm to hold said platen in non-printing position and including a pivotally mounted arm, and means yieldably connected to said arm and including selectively operable means for controlling the operation of said latching means.

10. In a device of the class described, a pivotally mounted arm having a part above its pivot and a part depending below the pivot therefor, a dog pivotally mounted at the lower end of said last named part, a cam plate upon which the dog rides, driving means and including a hook engageable with said last named part to effect ascent of the first named part of said arm and permit free descent of said first named part and including another part engageable with said dog when said dog rides off the end of said cam plate when said arm moves into a predetermined position in the descent thereof, a boss on said last named part, a latch adapted to engage said boss to hold said first named part in an elevated position into which it is moved by said driving means whereby said driving means may be operated without a consequent descent and ascent of said first named part when said latch is engaging said boss, and selectively operable means for controlling operation of said latch.

11. In a device of the class described, a pivotally mounted arm having a part above its pivot and a part depending below the pivot therefor, a boss at the lower end of said last named part, a latch engageable with said boss to hold the first named part of said arm in an elevated position, retracting means including a yieldable portion for retracting said latch to permit descent of said first named part from said elevated position, and selectively operated means for controlling the operation of said retracting means.

WALTER T. GOLLWITZER.
